INK FOUNTAIN

Edwin W. Goodwin, New Rochelle, N. Y., assignor
to R. Hoe & Co., Inc., New York, N. Y., a corporation of New York

Application October 9, 1945, Serial No. 621,258

2 Claims. (Cl. 101—364)

1

This invention relates to ink fountains for use with printing machines and more particularly to a retractable mounting for a fountain blade that is located in the ink fountain and which cooperates with a fountain roller.

The fountain roller of a printing machine is commonly mounted to rotate in an ink fountain from which it picks up a quantity of ink. A flexible metallic fountain blade engages the surface of the fountain roller and removes excess ink therefrom. Occasionally it is desirable to clean the ink fountain with its fountain blade and roller and in order to facilitate this operation, the invention has for one of its objects the provision of an improved mechanism for mounting a fountain blade.

Another object of the invention is the provision of a new and improved fountain blade mechanism wherein the fountain blade can be moved from engagement with the fountain roller for cleaning and then reset with ease and without disturbing its adjustment.

Other objects of the invention will appear in the following description and claims.

A preferred embodiment of the invention is shown in the accompanying drawings wherein:

Figure 1 is a view partly broken away showing an ink fountain with its fountain roller and cooperating fountain blade mounted in accordance with the invention, the parts being shown as seen in the direction of arrow 1 in Figure 2;

Figure 2 is a sectional view on the line 2—2 of Figure 1 and as seen in the direction of the arrows;

Figure 3 is a fragmentary view of a portion of the mechanism shown in Figure 2 as seen in the direction of the arrow 3; and

Figure 4 is a fragmentary sectional view on the line 4—4 of Figure 1 as seen in the direction of the arrows.

A conventional fountain roller 10 is rotatably supported in an ink fountain 11 by a pair of roller bearings 12 that are held in bearing housings 13 formed in side members 14 of the fountain, by screws 16 and plates 17. The roller 10 is rotated in the direction shown in Figure 2 by means not shown, and a doctor roller 18 is rotatably mounted in a pair of oscillatable arms 19 and is moved alternately into engagement with the roller 10 and an ink distributing roller (not shown).

The ink fountain 11 includes side frame members 14, and a fountain frame 21, that is secured in the printing machine by bolts 22, and has an upper machined surface 23 on which is slidably

5 mounted a lower clamping member 24. The lower clamping member is slidably held to the frame 21 by a plurality of bolts 26. Each bolt is provided with a washer 27 and extends through 10 a U-shaped slot 28 in the frame 21, and is screwed into a threaded hole 29 in the clamping member 24. An upper clamping member 31 is secured to the lower clamping member 24 by bolts 32 and the two clamping members thus 15 form a blade holder which firmly holds a fountain blade 33 in proper position. A longitudinally extending recess 34 having an inclined surface 36 is provided in the upper surface 23 of the fountain frame, and a lip 37 formed on the edge 20 of the lower clamping member 24 cooperates with the inclined surface 36 to provide a fountain blade lifting device. A bar 38, secured to the forward edge of the frame 21, is held in place by a plurality of bolts 39. A plurality of threaded holes 41 extend through this bar and each hole carries a threaded thumb screw 42 having a head 43, whereby the edge of the fountain blade 33 may be conveniently adjusted with relation to the fountain roller 10.

25 A means for slidably moving the clamping members 24 and 31 together with the doctor blade 33, toward and away from the fountain roller 10, includes a pair of levers 45, pivotally supported on pins 44, held in bearing blocks 46, that are secured to the frame 21 by screws 50. The upper end of each lever 45 enters a hole 47 provided in the lower clamping member 24. A slot 48 is provided intermediate of the ends of each lever 45. Each end of a shaft 49 that is 30 rotatably supported in the bearing blocks 46 carries an eccentric pin 53 which passes through the slotted holes 48 in the levers 45, and the shaft is provided with a diametrical hole 54 in which an operating rod 56 may be inserted.

35 40 Adjustable means for limiting the forward movement of the clamping members 24 and 31 and thus the doctor blade 33 is provided and includes a stop 57 (Figure 4) secured to the lower clamp member 24. This stop cooperates 45 with a cap screw 58 carried by the frame 21 and has a lock nut 59.

45 In operation, when it is found desirable to clean the ink fountain 11, the bolts 26 are loosened, the rod 56 is inserted into the hole 54 and the shaft 49 is turned counter-clockwise, as 50 seen in Figure 2, approximately 90 degrees. This causes the eccentric pins 53 to swing the levers 44 and 45 and thereby move the clamping members 24 and 31 to withdraw the fountain blade 33 from engagement with the fountain roller 10. As the 55

lower clamp member moves backward, the lip 37 moves up the inclined surface 36 of the recess 34 and onto the upper machined surface 23 of the frame 21, thus raising the fountain blade from engagement with the adjusting screws 42. With the fountain blade so withdrawn from the fountain roller, the ink fountain and roller may very easily be cleaned. After the cleaning, the rod 49 is rotated in the reverse direction until the stop 57 engages the screw 58, thus returning the fountain blade to its original position, after which the bolts 26 are tightened. Since the lip 37 rides on the machined surface 23, the forward edge of the blade is held high enough to clear adjusting screws 42, during its return movement. The fountain blade may thus be moved away from its normal position and later returned to the same position without disturbing its adjustment with respect to the fountain roller.

It will be understood that the invention may be embodied in other specific forms without departing from the spirit or essential attributes thereof, and it is therefore desired that the present embodiment be considered in all respects as illustrative and not restrictive, reference being made to the claims rather than to the foregoing description for an indication of the scope of the invention.

What I claim is:

1. In a printing ink fountain having a frame supporting a fountain blade with an edge adjacent a fountain roller and adjusting means associated with the frame for close adjustment of the spacing between the edge of the blade and the periphery of the roller; the combination therewith of a blade holder fitted to a seat on the frame and arranged to hold the blade, means to

move the holder and the blade forward on the frame into operating position relative to the roller and backward away from the roller, a lip on the holder, and a lip engaging surface on the frame arranged to engage the lip as the blade is moved backward.

2. In a printing ink fountain having a frame supporting a fountain blade with an edge adjacent a fountain roller and adjusting means associated with the frame for close adjustment of the spacing between the edge of the blade and the periphery of the roller; the combination therewith of a blade holder having a surface fitted to a corresponding surface on the frame, one said surface having a longitudinal recess and the other surface having a lip normally extending into the recess, and means to move the blade holder rearward to withdraw a blade carried thereby from its normal operating position, the said lip being arranged to move out of the recess and raise the blade holder as the blade is moved rearward and thereby lift the blade from the adjusting means.

EDWIN W. GOODWIN.
